ELEVATOR UNIT FOR CONVEYERS

Eben D. Dahlman, Grandy, Minn.

Application May 10, 1941, Serial No. 392,881

3 Claims. (Cl. 198—197)

This invention relates to a conveyer and particularly to an elevator unit for a conveyer.

While the invention is applicable to various types of conveyers it specifically is designed to be used on the chain conveyer of a potato picking machine or similar machine. Such conveyers comprise a plurality of links having straight intermediate portions which extend from each side of the conveyer in parallel relation. Said links have their ends bent to form loops so that they can be interengaged to form a continuous open-work conveyer of the chain type.

It is an object of this invention to provide an elevator unit in connection with such a conveyer, which unit is extremely simple and which can be easily and inexpensively produced.

It is a further object of the invention to provide an elevator unit for a link of a conveyer comprising a flat bar extending transversely of said conveyer and in a plane substantially perpendicular to the plane thereof, which bar is provided with means to prevent bruising of the potatoes or other materials handled.

It is more specifically an object of the invention to provide an elevator unit comprising a flat upstanding bar having a facing of yielding material at its front side which preferably extends above the top of said bar, said bar being oscillatably mounted on the intermediate portion of a link and having means extending to and engaging the top of the next adjacent link.

These and other objects and advantages of the invention will be fully set forth in the following description made in connection with the accompanying drawing in which like reference characters refer to similar parts throughout the several views and in which:

Fig. 1 is a perspective view of the elevator unit and link supporting the same;

Fig. 2 is a top plan view of the elevator unit showing a plurality of links of the conveyer;

Fig. 3 is a view in side elevation as seen from the right of Fig. 2; and

Fig. 4 is a vertical section taken on line 4—4 of Fig. 2 as indicated by the arrow.

Referring to the drawing a portion of a chain or link conveyer such as now commonly used on potato harvesting and other harvesting machinery is shown. This conveyer comprises a plurality of links 10 each having a rectilinear intermediate portion 10a of rod-like or substantially cylindrical form. Each link has its ends bent rearwardly and then upwardly and forwardly to form a loop 10b. As shown in Figs. 2 and 3, the portions 10a can be disposed in the loops

10d so that the links are interengaged and form a flexible conveyer having the parallel portions 10a extending from side to side thereof. It is desirable to have elevator units in connection with the conveyer to assist in carrying the potatoes or other articles upward thereon.

In accordance with the present invention this elevator unit comprises a flat bar 11 having rigidly secured to its rear side clip members 12. Clip members 12 are preferably formed of simple strips of metal substantially rectangular in transverse cross section. These members 12 have their front ends bent downwardly to form semi-cylindrical loops 12a through which the intermediate portion 10a of the link 10 extends. Members 12 are thus oscillatable on said portions 10a. While members 12 might be variously secured, in practice it has been found to be very easy and suitable to spot-weld members 12 to bar 11 and the members 12 are illustrated as so connected to bar 11. Members 12 have portions 12b extending rearwardly from the top of loops 12a a sufficient distance to overlie the intermediate portion 10a of the next adjacent link. Bar 11 extends upwardly in a plane substantially perpendicular to the plane of the conveyer and a layer of yielding material 13 is secured to the front face of said bar 11. While various materials might be used, in practice it has been found suitable and convenient to use a layer of rubber and member 13 is so illustrated. Member 13 is illustrated as secured to the strip 13 by the rivets 14 having their heads at the front sides thereof countersunk into or embedded in layer 13.

In operation the unit comprising bar 11 and attached parts will move with the conveyer and with the conveyer link on which it is mounted. The potatoes or other material engaging the front side of layer 13 will tend to hold the same in vertical position or to swing the top thereof rearwardly. The bar 11 and layer 13 will be held in substantially vertical position by the engagement of portions 12b with the next link. However, the unit comprising bar 11 and attached parts may oscillate about the link as the conveyer passes around the sprocket or supporting members. The potatoes or other articles will be prevented from rolling downwardly on the conveyer and will be carried upwardly or with the conveyer by the unit. The layer 13 of yielding material will prevent bruising of the potatoes or other articles and it will be noted that layer 13 extends above the upper edge of bar 11. Any potatoes falling or dropping onto the conveyer will engage the upper edge of layer 13 and will

thus be prevented from engaging the hard upper edge of bar 11. The potatoes will thus be prevented from being bruised.

From the above description it is seen that I have provided a very simple and efficient elevator unit for a conveyer of the type disclosed. The unit can be easily and quickly made from easily procured material.

The elevator unit is quite rugged and will thus be very durable. The same has been amply demonstrated in actual practice found to be very successful and efficient and is being commercially made.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. An elevator unit for the conveyer chain of a potato picker, said chain being constructed and arranged to support potatoes upon its upper run and being composed of similar spaced links each having an intermediate straight rod-like portion, spaced clips having their ends bent into loops through which said portion of one of said links extends and in which it is revoluble, said clips extending rearwardly from said loops substantially in the plane of said conveyer to overlie the intermediate portion of the next adjacent link, a flat bar spot-welded to said loops adjacent the front ends thereof and disposed to extend upwardly in a plane substantially perpendicular to the plane of said conveyer and substantially throughout the width thereof and a layer of

rubber-like material secured to the front face of said flat bar and extending slightly above the upper edge thereof.

2. An elevator unit for a conveyer chain of a potato picker, said chain being constructed and arranged to support potatoes upon its upper run and being formed of similar equally spaced links each having an intermediate rectilinear rod-like portion, a pair of spaced members having portions through which said portion extends and in which it is oscillatable, said members extending rearwardly from said portion to overlie the intermediate portion of the next adjacent link, a flat bar rigidly secured to the front side of said members and extending upwardly in a plane substantially perpendicular to the plane of said conveyer and a layer of yielding material overlying the front side of said flat bar and extending a short distance above the upper edge thereof.
3. The combination with a conveyer chain of a potato picker, said chain being composed of equally spaced links each having a transversely extending intermediate rod-like portion and being arranged to support and carry potatoes on the upper run thereof, of a member having spaced clips with portions extending downwardly and around one of said intermediate portions so as to be swingable thereon, said clips having portions extending rearwardly substantially parallel to the plane of said conveyer to overlie and engage the adjacent link in the rear thereof, said member having a plate-like portion carried by said clips extending substantially vertically to the plane of said conveyer and throughout substantially the whole width thereof and a facing of yielding material on the front of said plate-like portion for engaging said potatoes.

EBEN D. DAHLMAN.
